CLAIM

The ornamental design for a lip balm holder, as shown and described.

DESCRIPTION

FIG. 1 is an environmental PERSPECTIVE view of an embodiment of the present invention;

FIG. 2 is a FRONT view of an embodiment of the present invention;

FIG. 3 is a BACK view of an embodiment of the present invention;

FIG. 4 is a SIDE view of an embodiment of the present invention;

FIG. 5 is a SIDE view of an embodiment of the present invention;

FIG. 6 is a TOP view of an embodiment of the present invention;

FIG. 7 is a BOTTOM view of an embodiment of the present invention; and,

FIG. 8 is an EXPLODED view of an embodiment of the present invention.

The broken lines depicting an animal in FIG. 1 illustrate environment. The remaining broken lines illustrate the bounds of the claimed design. None of the broken lines form part of the claimed design.

1 Claim, 5 Drawing Sheets
